US00D752790S

(12) **United States Design Patent**
Hine et al.

(10) **Patent No.:** US D752,790 S
(45) **Date of Patent:** ** Mar. 29, 2016

(54) **LIGHTING DEVICE**

(75) Inventors: **David J. Hine**, Syracuse, NY (US);
Matthew R. Gortner, Manlius, NY (US); **William R. Narpes**, North Ridgeville, OH (US)

(73) Assignee: **Energizer Brands, LLC**, St. Louis, MO (US)

(**) Term: **14 Years**

(21) Appl. No.: **29/428,476**

(22) Filed: **Jul. 31, 2012**

(51) **LOC (10) Cl.** 26-02

(52) **U.S. Cl.** USPC D26/39

(58) **Field of Classification Search**

(57) **CLAIM**

We claim the ornamental design for a lighting device, as shown and described.

DESCRIPTION

FIG. 1 is a front perspective view of the design with the headstrap and lens attached.

FIG. 2 is a front perspective view of the design with the lens attached.

FIG. 3 is a front perspective view of the design.

FIG. 4 is a rear perspective view of the design.

FIG. 5 is a right side view of the design. The left side view of the design is a mirror image of the right side view.

FIG. 6 is a front view of the design.

FIG. 7 is a rear view of the design.

FIG. 8 is a top view of the design.

FIG. 9 is a bottom view of the design.

FIG. 10 is a front perspective view a second embodiment of the design with the headstrap and lens attached.

FIG. 11 is a front perspective view of the design with the lens attached.

FIG. 12 front perspective view of the design.

FIG. 13 is a rear perspective view of the design.

FIG. 14 is a right side view of the design. The left side view of the design is a mirror image of the right side view.

FIG. 15 is a front view of the design.

FIG. 16 is a rear view of the design.

FIG. 17 is a top view of the design.

FIG. 18 is a bottom view of the design.

FIG. 19 is a front perspective view a third embodiment of the design with the headstrap and lens attached.

FIG. 20 is a front perspective view of the design with the lens attached.

FIG. 21 front perspective view of the design.

FIG. 22 is a rear perspective view of the design.

FIG. 23 is a right side view of the design. The left side view of the design is a mirror image of the right side view.

FIG. 24 is a front view of the design.

FIG. 25 is a rear view of the design.

FIG. 26 is a top view of the design; and,

FIG. 27 is a bottom view of the design.

The broken lines depict environmental subject matter only and form no part of the claimed design.
